PRINTING MACHINE

Joseph Krell, Berlin-Zehlendorf, Germany

Application January 6, 1934, Serial No. 705,601
In Germany January 13, 1933

20 Claims. (Cl. 101—65)

My invention relates to printing machines, for instance, to machines for printing addresses, lists, forms, etc.

More particularly, my invention relates to printing machines which are equipped with a rotary or turret-like printing head and with a plurality of printing platens on the head, for printing from printing plates.

In the operation of such a machine, the individual platens of the printing head are moved into printing position and locked in printing position successively and by automatic means connected to the drive of the machine, and the printing plates are successively presented to the platens at the printing station, also by automatic means connected to the drive of the machine.

In machines of the type described, it has already been proposed to provide means for rotating the printing head, and for locking it in the printing positions of its platens, in combination with mechanism for operating both the rotating and the locking means, and with a single member, such as a link, for connecting the mechanism to the means.

It is an object of my invention to improve a machine of this type.

To this end, I provide separate members intermediate the mechanism and the means. One of the members is provided for operatively connecting the mechanism to the head-rotating means, and the other member is provided for operatively connecting the mechanism to the head-locking means, for releasing such means.

A machine according to my invention is normally equipped with a rocking printing arm, and the aforesaid mechanism is operated in time with the movement of the arm. The mechanism, in turn, operates the head-rotating, and releases the head-locking means. In so far, it is similar to the old machine referred to (and described in German Patent 430,625) but while in this machine a single member or link is provided for operating both means from the mechanism, i. e., rotating the head, and releasing its locking means, I provide separate members or links connected to the mechanism, one for operating the head-rotating means, and the other for releasing the head-locking means.

Apparently, my novel machine is complicated by the extra member or link but this complication is amply made up for by the simplification of the means for rotating the printing head, and for releasing its locking means. If a single link is provided, as in the old machine, the means become so very complicated as to be liable to fre-

quent failures, and to undergo excessive wear. In my novel machine, on the other hand, the means, as will appear from the specification and drawings, are quite simple elements which are not only reliable in operation and not subjected to excessive wear, but are also manufactured without difficulty, and the initial cost of the machine is reduced in proportion.

Another drawback of the old machine which also results from its single member or link, is the abrupt starting of its head-rotating means. The single link in the old machine, while releasing the locking means for the printing head gradually, as required, cannot start the means for rotating the head as gradually because, being called upon to perform the two functions, the link, after releasing the head, acquires a certain velocity at which it starts the rotation of the head. This velocity is comparatively high and so the printing head starts for its rotation with a jerk. This is undesirable not only because the operation of the machine becomes noisy, but also because the momentum of the abruptly moving head still further increases the—already excessive—wear of the parts.

By providing the extra member or link according to my invention, I also eliminate this drawback of the old machine, as the mechanism which is operatively connected to the two means by the individual members or links, can be so designed that both means are started gradually as the velocity of every link at the start may be determined as required. There is no difficulty whatever about starting the head-rotating means at the same, or substantially the same, low velocity as the velocity at which the head is released.

The mechanism and the members or links connecting it to the individual means, are so designed that, as the printing arm moves upwards into its inactive or non-printing position, one of the members or links releases the printing head and thereupon the other member or link turns the released head for moving another platen into printing position. The head is locked in this position while the printing arm moves downwards for performing the printing operation in cooperation with one of the printing plates at the printing station.

It is another object of my invention to provide means for effecting a still more gradual start of the head-rotating means than is already effected by the gradually moving link or member. To this end, I interpose cushioning means such as a block of rubber or the like, between the head

rotating means and the corresponding member or link.

It is still another object of my invention to provide means for preventing overthrowing of the printing head under all conditions. To this end, I provide a brake, for instance, a friction brake, which tends to counteract the rotation of the head.

In the accompanying drawings, a machine embodying my invention is illustrated by way of example.

In the drawings

Fig. 1 is a plan view showing the printing arm and a portion of the table of the machine,

Fig. 2 is a partly sectional end elevation viewed in the direction of arrow II in Fig. 1,

Fig. 3 is a section on the line III—III in Fig. 2, and

Fig. 4 is an elevation like Fig. 2 and also viewed in the direction of arrow II in Fig. 1, but showing the parts in another position.

Referring now to the drawings, the machine illustrated by way of example is an address-printing machine, with a table 1, a hopper 2 for the reception of a supply of printing plates 3, and a track or guideway 4 in the table 1 for the printing plates 3 to move in toward the printing station 5. That printing plate 3 which is lowermost in the pile of plates in the hopper 2, is engaged by a slide or cross head and pushed along the track 4 by intermittent movements of the slide, until finally it arrives at the printing station where it is printed. The printing plates which have been printed, are ejected and collected.

The means for moving or feeding the printing plates 3 along the track 4 are old in the art and will not be shown and described as they have no bearing on the present invention.

A printing arm 6 is fulcrumed on the table 1 at 7 and equipped with a tail portion 6' which extends downwards through a hole in the table and is connected to a link 8 to which reciprocation is imparted from a suitable drive. The drive, like the printing-plate feeding means, is old in the art and will not be shown and described.

At the side of the printing arm 6 which faces the printing station, the arm is equipped with a pair of lugs 9 and 99 which are spaced apart for the reception of the printing head 12, as will be described. At the opposite side of the printing arm 6, it is equipped with two more lugs 10 and 11 which support a part of the mechanism by which the means for rotating and locking the printing head 12 are operated, as will also be described.

Referring now to Fig. 3, the printing head 12 has a tubular boss with which it is free to rotate about a fixed pin 22 in the lugs 9 and 99. In the present instance, the printing head 12 is equipped with three platens and with three radial hollow arms, one of which is shown in axial section at 14 in Fig. 3, for supporting the platens. At its free end, every arm 14 supports a plate 13 which is preferably integral with the arm, and is equipped with four screws 18. The threaded outer ends of the screws 18 engage in threaded bosses on the platens 15', 16', and 17'. The platens are equipped with pads 15, 16, and 17, respectively, of rubber or other suitable material, and the pads may be subdivided, as shown for the pad 15 in Fig. 1 which consists of three individual pads.

Means are provided for varying the distance of the platens and pads from the axis of the printing head 12. The arms 14 have internal

threads in which engage male threads on pins 19. The pins 19 are equipped with knurled handles 20 for turning them and their outer ends are equipped with a socket for the reception of a ball 21. A corresponding socket is formed in the inner face of the platen, as shown for the platen 15' in Fig. 3.

This figure shows the inner final position of the platen 15'. When it is desired to move the platen further away from the axis of the printing head, the screws 18 are unscrewed and the pin 19 is turned by its knurled handle 20. The thrust of the threaded pin 19 is transmitted to the platen 15' and the platen is moved further away from the axis of the printing head 12. When the platen has been moved into the desired position by the means described, the screws 18 are set so as to force the socket in the platen 15' against the ball 21. Obviously, for shortening the distance of a platen from the axis of the printing head, the pin 19 is turned in the opposite direction.

As mentioned, the printing head 12, with its three internally threaded arms 14, its three plates 13, and its three platens 15', 16' and 17', each having its pad 15, 16, and 17, respectively, is mounted to rotate freely on the fixed pin 22 in the lugs 9 and 99. Secured on that end of the boss of the printing head 12 which is at the right in Fig. 3, is an indexing disk 23, with three notches 24, 25, and 26, as shown in Figs. 2 and 4. A pinion 27 is mounted to turn freely on the pin 22, its boss being held against axial displacement by the disk 23 at one end, and by the lug 99 at the other. This pinion has teeth only on a portion of its perimeter and its untoothed portion is formed as a lever 28, with a pawl 29 fulcrumed on its free or outer end. A spring 29', Fig. 1, tends to hold the pawl engaged with the perimeter of disk 23 and causes the pawl to drop into notches 24, 25 and 26 if it registers with one of them, as shown for the notch 26 in Fig. 2. A sector 30 is mounted to oscillate about a pin 31 in the lug 99, Fig. 1. The sector meshes with the teeth of pinion 27 and has a tail portion 32 which extends beyond the pin 31 and, in a suitable recess, receives a cushion 33, for instance, a block of rubber.

The sector 30, the pinion 27 and the parts operatively connected to the pinion, serve for rotating or indexing the printing head 12. The means for operating the sector 30 will now be described. A fork 34, with a pair of lugs 34' and 34'' at opposite sides of the tail portion 32, is free to turn about the pin 31 about which the sector 30 oscillates. The lower lug 34' of the fork 34 engages below the lug or tail portion 32, and the upper lug 34'' has an adjustable screw 35 which bears on the cushion 33.

36 is the member or link by which the fork 34 is connected to the mechanism for operating both the head-rotating and head-locking means on the printing arm 6. The link 36 which has the form of a flat horse shoe in order to avoid interference with the printing arm 6 in certain positions, see Fig. 4, is pivoted to the fork 34 at one end, and to a crank pin 37 in a crank disk 38 at its other end. The crank disk is secured on a shaft 39 which is mounted to rotate in the two lugs 10 and 11 of the printing arm, Fig. 1. The boss 41 of a pinion 40 is free to turn on the shaft 39. A clutch is provided for connecting the boss 41 and the pinion 40 to the shaft 39. The clutch comprises a disk 42 on the boss 41 and a block 43 which is keyed on the shaft 39.

A pin 44 is mounted to slide in a bore of the block 43 and equipped with a transverse pin 45 which slides in a slot of the block 43. The clutching pin is equipped with a knurled head 44' for shifting and turning it. In the position illustrated in Fig. 1, the pin connects the two clutching members 42 and 43 and its final position is defined by the transverse pin 45 which bears against the inner end of the slot. When 10 the pin 44 is retracted the pinion 40 is free to turn on the shaft 39. In the retracted position of the pin, its transverse pin 45 engages in a recess 47 in the face of the block. In this manner, the two final positions of the pin 44 are 15 defined by the transverse pin 45. When the pin 44 connects the clutching members 42 and 43, rotation of the pinion 40 is transmitted to the shaft 39. A sector 48 which is free to turn about a pin 49 in the lug 10, meshes with the pinion 40. 20 The sector has a tail portion 50 which through a link 51, is connected to a bellcrank 52. This bellcrank is fulcrumed on the tail portion 6' of the printing arm 6 at 54 and its shorter arm 53 is anchored with respect to a bracket 56 below 25 the table 1 by a link 55. It will be understood that, as the printing arm 6 performs its rocking movement about 7 under the action of the link 8, the pivot 54 of the bellcrank 52 describes an arc about 7 and, as the shorter arm 53 of the bellcrank is anchored in the manner described, the link 51 is reciprocated and the sector 48 turned 30 about its pin 49.

The disk 38, with the parts connected to it, makes up the "mechanism" referred to. The 35 means for locking the printing head and its connection with the mechanism will now be described. A bellcrank with a longer arm 59 and a shorter arm 60 is mounted to turn freely on the boss of the pinion 27, as best seen in Fig. 3. 40 Its longer arm 59 is connected to a crank pin 57 in the disk 38 by a link 58, which, like the link 36, has the form of a flat horse shoe. The two crank pins 37 and 57 are not diametrically opposite on the disk 38, for a purpose to be presently described.

A dog 61 is fulcrumed on the shorter arm 60 of the bellcrank at 60', as best seen in Fig. 4. The dog is a double-armed lever whose arm 61' is connected to a spring 62. The other end of 50 the spring 62 is attached to an eye 59' on the bellcrank. The spring tends to pull the arm 61' toward the eye 59' and to move the dog 61 outward. The outward movement of the dog under the action of the spring 62 is limited by a suitable 55 check, not shown.

The dog 61 cooperates with a locking pawl 64 which is mounted to turn on the pin 31, like the sector 30, and adapted to engage in the notches 24, 25 and 26 with its free end. Fig. 2 shows the 60 locking pawl engaging in the notch 24. 63 is a roller on the pawl 64 for cooperation with the dog 61. The locking pawl is also a double-armed lever and a spring 65 is connected to its shorter arm 64' with one end, the other end of the spring 66 being anchored on the printing arm 6.

In the manner described, the "mechanism", the disk 38 etc., is connected to the head-rotating means, the sector 30 etc., by the member or link 36, and to the head-locking means, the pawl 64, by the member 58. The operation of the machine 70 will be described below.

The "cushioning means" referred to in the introduction is the rubber block 33 in the tail portion 32 of the sector 30.

The "means for preventing overthrowing of

the printing head" which has also been referred to in the introduction, will now be described with reference to Fig. 3. The means is a friction brake whose casing 66 is keyed on the boss of the printing head 12. The outer end wall of the casing is a plate 67 which is held against rotation on the lug 9 but is mounted to slide on the boss of the printing head. A thin iron plate 68 is secured in the outer wall or barrel of casing 66, and a similar plate 69 is secured on the boss of end plate 67. Three plates 70 of felt or other suitable material are inserted between the iron plates, the casing 66 and the end plate 67, and the friction members are compressed by a spring, or preferably several springs, 71, acting on the 15 end plate. The pressure of the spring, or springs, is regulated by a screw 72.

When the printing head 12 rotates with respect to the printing arm, i. e., its lug 9, the friction produced between the elements of the 20 brake counteracts the movement of the printing head.

The operation of the machine is as follows:

The printing plates 3 are fed to the printing station 5 along the track 4 in the manner described and by the old means not shown. Every printing plate must remain at the printing station 5 during as many printing operations as there are platens on the printing head 12; in the present instance, during three operations.

Assume that the first print from a printing plate 3 at the printing station 5 is made by the platen 15' with its divided pad 15. The print is made on an envelope, a sheet, a form, or the like, by means of a ribbon, not shown, by which the type on the printing plate is reproduced on the sheet or the like under the pressure of the platen. Fig. 2 shows this position of the parts. The printing head is locked in printing position for the platen 15' by the pawl 64 which engages 40 in the notch 24 of the indexing disk 23, and the pawl 29 on the lever 28 engages in the notch 26, ready for rotating the printing head after the pawl 64 has been thrown out.

When the first print has been made, the printing arm 6 is moved upwards from the position in Fig. 2 and into its inactive position in Fig. 4 by the drive of the machine, not shown, and the link 8. During the upward movement of the printing arm, the sector 48 of the "mechanism" is turned about its pin 49 in clockwise direction from the position in Fig. 2, by the link 51 and the means connected to such link. When the sector starts for its movement from the position in Fig. 2, it rotates the pinion 40 and, if the clutch 42, 43 is thrown in, the shaft 39 and the crank disk 38 are rotated in the direction of arrow 80, i. e., anti-clockwise.

As soon as the crank disk 38 begins to rotate, it moves the link 58 in the direction of the arrow 60 81, Fig. 2, and turns the bellcrank 59, 60. As, however, the crank pin 57 on the disk 38 is in its dead-centre position with respect to the link 58, the link moves very slowly at first and the dog 61 whose operative connection to the bellcrank 59, 60 has been described, and which in Fig. 2 is ready for engaging the roller 63 on the pawl 64, lifts the pawl from its notch 24 quite gradually and without a jerk. All the same, as the velocity of the link 58 in the direction of arrow 81 steadily increases, the printing head 12 is released soon after the printing arm 6 has started for its upward movement.

Obviously, the crank pin 37, being on the same crank disk 38 as crank pin 57, begins to move as

soon as the disk is rotated. But it will be remembered that the two crank pins are not pitched at 180 degs. to each other, and it will appear from Fig. 2 that the crank pin 37 lags in the direction 5 of arrow 80. Therefore, at first the crank pin 37 imparts to its link 36 a movement in the same direction as link 58, and in opposite direction to the arrow 75. During the first stages of the rotation of disk 38, therefore, the fork 34 is turned 10 anticlockwise and its lug 34' turns the sector 30 in the same direction. The pinion 27 turns the lever 28 in clockwise direction, as indicated by arrow 73, and the pawl 29 is wholly or partly moved out of the notch 26 which has not any influence 15 on the position of the printing head. The lag of the crank pin 37 is so determined that the pawl 64 releases the printing head as soon as the crank pin 37 has moved beyond a position which corresponds to its dead-centre position with respect 20 to link 36. Upon further rotation of the crank disk 38, the link 36 moves in the direction of arrow 75, Fig. 2. The movement of the link is slow at first, for the reasons stated with reference to the crank pin 57 and the link 58, and the 25 fork 34 is turned slowly in clockwise direction. Its lug 34'', through the screw 35 and the rubber block 33, turns the sector 30 also in clockwise direction while the pinion 27 and its lever 28 are turned anti-clockwise, arrow 76, and in the same 30 direction as the long arm 59 of the bellcrank by which the pawl 64 had previously been released, arrow 74. Abrupt operation of the sector 30 is prevented not only by the gradual start but also by the damping action of the rubber block 33. 35 Turning of the lever 28 in the direction of arrow 76 and against arrow 73 causes the pawl 29 to retrieve the backward movement it had undergone during the initial stages of the movement of crank pin 37 until it engages the notch (26 in Fig. 2) 40 and the indexing plate 23 and the printing head are rotated in the direction of arrow 74, slowly at first, until finally, when the printing arm is in its inactive position, Fig. 4, the platen 16' has moved into printing position. 45 It will be understood that by the means described the locking pawl 64 is retracted slowly and without jerking before the lever 28 is operated for turning the indexing disk 23. The operation of the indexing disk is delayed by the backward movement of the lever 28, and the disk and printing head are only started after this backward movement has been retrieved, and then quite slowly. A single member, as in the old machine referred to, performs the releasing operation as 50 gradually as required but as it also performs the rotation of the printing head, its velocity is too high. The printing head is started with a jerk, with the undesirable consequences set out above. 55 By providing the two members 36 and 58 which are, comparatively speaking, independent, the releasing and rotating operations are performed under the conditions required. 60 The operation becomes still more gradual by the damping means (rubber block 33) and the brake 66—70. 65 When the inactive position in Fig. 4 has been attained, the notch 25 is in line with the pawl 64 and the pawl is thrown in by its spring 65, locking 70 the printing head in the position corresponding to the operation of platen 16'. 75 Upon the subsequent downward movement of the printing arm 6, the parts return into the positions shown in Fig. 2, except for the fact that the platen 16' is now in printing position. By the means described, the sector 48 is turned anti-clockwise and the crank disk 38 is rotated clockwise, arrow 77. This rotation of the crank disk 38 causes the link 36 to return in the direction of the arrow 78, and the link 58 to return in the direction of arrow 79, toward the positions in Fig. 2. The link 36 turns the sector 30 in anti-clockwise direction, through the medium of fork 34, and the sector, through pinion 27, moves the lever 28 and the pawl 29 in clockwise direction until 10 the pawl engages in the notch 24 of indexing plate 23. The link 58 moves in the direction of arrow 79 and, in so doing, turns the longer arm 59 of the bell crank in clockwise direction. The dog 61 now moves past the roller 63 on the pawl 64 15 without influencing the pawl, this being permitted by the spring 62. 15 When the second print is made from the printing plate 3 at the printing station 5, the parts are in the same positions as in Fig. 2, but the operation of printing is now performed by the platen 16', the pawl 64 is in the notch 25 and the pawl 29 is in the notch 24, of the indexing disk 23. When the printing operation has been performed by the platen 16', the printing arm is raised again, the 20 third platen 17' is moved into printing position, and the third print is made. 25 When the three prints have been made from a given plate 3 at the printing station, a fresh printing plate is presented at the printing station 30 5, and upon the upward movement of the printing arm subsequent upon the printing with the third platen 17', the printing head 12 is rotated in the direction of arrow 74, Fig. 2, to present the first platen 15' to the printing plate which is at 35 the station 5. Obviously, all parts including the platens 15', 16', and 17' are now again in the positions shown in Fig. 2. 40 If the clutch 42, 43 is thrown out by retracting the pin 44, the "mechanism" is inactive, the printing head 12 remains locked by the pawl 64 and the platens are not alternately moved into printing position. 45 It is understood that I am not limited to any definite number of platens on the printing head but may provide as many, or as few, platens as may be desired or required. 50 I claim: 55

1. In a printing machine, a printing arm, a printing head mounted to rotate on said arm, printing platens on said head, means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, and another member operatively connecting said mechanism to said head-locking means. 60
2. In a printing machine, a printing arm, a printing head mounted to rotate on said arm, printing platens on said head, means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, and another member operatively connecting said mechanism to said head-locking means; said mechanism being so designed as to start gradually the two means to which it is connected. 65

3. In a printing machine, a printing arm, a printing head mounted to rotate on said arm, printing platens on said head, means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, and another member operatively connecting said mechanism to said head-locking means; 5
- 10 said mechanism to said head-rotating means, and another member operatively connecting said mechanism to said head-locking means; said mechanism being so designed as to first operate the member which is connected to the head-locking means, and thereupon the other member.
- 15 4. In a printing machine, a printing arm, a printing head mounted to rotate on said arm, printing platens on said head, means for rotating said printing head, means for locking said printing head against rotation in as many positions as there are platens on the head, a rotary part, mechanism operatively connected to said arm for intermittently rotating said rotary part, a member operatively connecting said part to said head-locking means, and another member connecting said rotary part to said head-rotating means, said last-mentioned member being connected to said part so as to lag with respect to the first-mentioned member.
- 20 5. In a printing machine, a printing arm, a printing head mounted to rotate on said arm, printing platens on said head, means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, cushioning means intermediate said member and said means, and another member operatively connecting said mechanism to said head-locking means.
- 25 6. In a printing machine, a printing arm, a printing head mounted to rotate on said arm, printing platens on said head, means for rotating said printing head, means for preventing overthrowing of said printing head, means for locking said printing head against rotation in as many positions as there are platens on the head, mechanism operatively connected to said arm for operating said head-rotating means and for releasing said head-locking means, a member operatively connecting said mechanism to said head-locking means, and another member operatively connecting said mechanism to said head-locking means.
- 30 7. In a printing machine, a printing arm, a printing head mounted to rotate on said arm, printing platens on said head, means for rotating said printing head, means for locking said printing head against rotation in as many positions as there are platens on the head, automatic means for throwing in said head-locking means, mechanism operatively connected to said arm for operating said head-rotating means and for throwing out said head-locking means, a member operatively connecting said mechanism to said head-rotating means, and another member operatively connecting said mechanism to said head-locking means.
- 35 8. In a printing machine, a printing arm, a pin on said arm, a rotary printing head comprising a tubular boss mounted to rotate on said pin, arms on said boss, a plate on every arm, a platen connected to said arm and said plate; means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, and another member operatively connecting said mechanism to said head-locking means.
- 40 9. In a printing machine, a printing arm, a pin on said arm, a rotary printing head comprising a tubular boss mounted to rotate on said pin, arms on said boss, a plate on every arm, a platen connected to said arm and said plate, and means for adjusting said platen with respect to said plate; means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, and another member operatively connecting said mechanism to said head-locking means.
- 45 10. In a printing machine, a printing arm, a pin on said arm, a rotary printing head comprising a tubular boss mounted to rotate on said pin, arms on said boss, a plate on every arm, a platen, means for securing said platen to said plate, a threaded member in every plate, means for rotating said threaded member, and a ball inserted between said threaded member and said platen; means for rotating said printing head, means for locking said printing head against rotation in as many positions as there are platens on the head, mechanism operatively connected to said arm for operating said head-rotating means and for releasing said head-locking means, a member operatively connecting said mechanism to said head-rotating means, and another member operatively connecting said mechanism to said head-locking means.
- 50 11. In a printing machine, a printing arm, a rotary printing head on said arm, friction means secured partly to said arm and partly to said head and arranged in interengaging relation, printing platens on said head, means for rotating said printing head, means for locking said printing head against rotation in as many positions as there are platens on the head, mechanism for operating said head-rotating means and for releasing said head-locking means, a member operatively connecting said mechanism to said head-rotating means, and another member operatively connecting said mechanism to said head-locking member.
- 55 12. In a printing machine, a movable printing arm, a rotary printing head on said arm, printing platens on said head, a fork mounted to oscillate on said arm about an axis which is parallel to the axis said head rotates about, a sector operatively connected to said fork, a pinion meshing with said sector, a pawl mechanism operatively connected to said pinion for rotating said printing head, means for locking said printing head against rotation in as many positions as there are platens on the head, driving mechanism adapted to move in time with said printing arm, a member operatively connecting said driving mechanism to said fork, and another member operatively connecting said driving mechanism to said head-locking means.

13. In a printing machine, a movable printing arm, a rotary printing head on said arm, printing platens on said head, a fork mounted to oscillate on said arm about an axis which is parallel to the axis said head rotates about, a pair of lugs on said fork, a sector mounted to oscillate on said arm about an axis which is also parallel to the axis of said head, a tail on said sector, cushioning means interposed between said tail and one of said lugs, a pinion meshing with said sector, a pawl mechanism operatively connected to said pinion for rotating said printing head, means for locking said printing head against rotation in as many positions as there are platens on the head, driving mechanism adapted to move in time with said printing arm, a member operatively connecting said driving mechanism to said fork, and another member operatively connecting said driving mechanism to said head-locking means.
14. In a printing machine, a rotary printing head, printing platens on said head, a pawl mechanism for rotating said printing head, a pawl for locking said printing head against rotation, an indexing disk on said printing head, with as many notches as there are platens on the head, for said pawl mechanism and said pawl to engage in, mechanism for operating said pawl mechanism and for releasing said pawl from said indexing disk, a member operatively connecting said operating mechanism to said pawl mechanism, and another member operatively connecting said operating mechanism to said pawl.
15. In a printing machine, a rotary printing head, printing platens on said head, means for rotating said printing head, means for locking said printing head against rotation in as many positions as there are platens on the head, a crank disk, mechanism for operating said crank disk, a link operatively connecting said crank disk to said head-locking means, and another link which is connected to said crank disk at one end so as to lag with respect to said first-mentioned link, and is connected to said head-rotating means at the other end; said links being so arranged with respect to the corresponding radii of said disk that they start slowly from their initial positions upon rotation of said disk.
16. In a printing machine, a rotary printing head, printing platens on said head, means for rotating said printing head, means for locking said printing head against rotation in as many positions as there are platens on the head, a bellcrank mounted to oscillate about the axis said printing head rotates about, a dog on said bellcrank, a spring for holding said dog in such a position as to engage the head-locking means in one direction for releasing them, and not to engage them in the opposite direction, a driving mechanism, a member operatively connecting
- said mechanism to said head-rotating means, and another member operatively connecting said mechanism to said bellcrank.
17. In a printing machine, a movable printing arm, a rotary printing head on said arm, printing platens on said head, means for rotating said printing head, means for locking said printing head against rotation in as many positions as there are platens on the head, a crank disk on said printing arm, a link operatively connecting said crank disk to said head-rotating means, another link connecting said crank disk to said head-locking means, a pinion on said printing arm, a clutch for connecting said pinion to said crank disk, a sector mounted to oscillate on said printing arm and to mesh with said pinion, and means adapted to move in time with the movement of said printing arm for operating said sector.
18. In a printing machine, a rotary printing head, printing platens on said head, means for rotating said printing head, means for locking said printing head against rotation in as many positions as there are platens on the head, mechanism for operating said head-rotating means and for releasing said head-locking means, a member operatively connecting said mechanism to said head-rotating means, and another member operatively connecting said mechanism to said head-locking means; said mechanism being so designed as to start gradually the two means to which it is connected.
19. In a printing machine, a rotary printing head, printing platens on said head, means for rotating said printing head, means for locking said printing head against rotation in as many positions as there are platens on the head, mechanism for operating said head-rotating means and for releasing said head-locking means, a member operatively connecting said mechanism to said head-rotating means, and another member operatively connecting said mechanism to said head-locking means; said mechanism being so designed as to first operate the member which is connected to the head locking means, and thereupon the other member.
20. In a printing machine, a rotary printing head, printing platens on said head, means for rotating said printing head, means for locking said printing head against rotation in as many positions as there are platens on the head, a rotary part, mechanism for intermittently rotating said rotary part, a member operatively connecting said rotary part to said head-locking means, and another member connecting said rotary part to said head-rotating means, said last-mentioned member being connected to said part so as to lag with respect to the first-mentioned member.

JOSEPH KRELL. 60
